UNITED STATES PATENT OFFICE.

ALEXANDER K. SCHAAP, OF NEW YORK, N. Y., ASSIGNOR TO SCHAAP AUTOMOBILE COMPANY, OF NEW YORK, N. Y., A CORPORATION OF NEW YORK.

COMPRESSED GAS AND AIR BURNER.

1,195,403.

Specification of Letters Patent. Patented Aug. 22, 1916.

Application filed June 16, 1915. Serial No. 34,363.

To all whom it may concern:

Be it known that I, ALEXANDER K. SCHAAP, a citizen of the United States, and a resident of the city of New York, county 5 of Kings, and State of New York, have invented a new and useful Improvement in Compressed Gas and Air Burners, of which the following is a specification.

The object of my invention is to provide 10 a burner which is adapted to receive mixed air and illuminating gas under pressure and to cause the same to be burned in a minimum time with a maximum concentration with a flame which may be varied without 15 changing the pressure of the mixture but by changing its proportions of gas and air so that a flame may be produced which is capable of simultaneously preheating and welding the parts on which it plays, which 20 parts may be made of the following metals, to wit: brass, bronze, copper, aluminum, aluminum alloys, malleable iron and cast iron.

A further object is to provide a suitable 25 flame for working or brazing in all these substances or for other purposes for which a flame may be applied.

A further object is to provide a burner 30 which may be adjusted for wide variations in the quality of air or the quality of gas supplied.

These, and other objects are accomplished 35 by my improved burner wherein a central high pressure portion has gaseous fuel flowing in the direction of the axis of the burner and this fuel is surrounded at the burner with a plurality of inwardly extending jets centered on the central flame or 40 portion of the burner so that the central portion is forced through these concentrated jets of lower pressure.

For a more particular description of my 45 invention, reference is to be had to the accompanying drawings, forming a part hereof, in which,

Figure 1 is a side elevation of one form 50 of my improved burner. Fig. 2 is an enlarged sectional view of a part of the structure shown in Fig. 1. Figs. 3 and 4 are plan views of details of the same. Fig. 5 is a cross-section of a portion of an enlarged burner. Figs. 6 and 7 show a slight 55 modification of the structure of Fig. 5, Fig. 7 being taken on the line 7-7 of Fig. 6, looking in the direction of the arrows.

Figs. 8, 9 and 10 show nozzles used in the structure shown in Fig. 5. Figs. 11 and 12 show a further modification, Fig. 12 being a sectional view, taken at right angles to the view shown in Fig. 11.

Throughout the various views of the drawings, similar reference characters designate similar parts.

My improved burner 1 may be made in many forms all of which embody the idea 65 of having a flame supplied by air and gas (ordinary illuminating gas) under pressure, issuing from a central opening 2 in the direction of the axis of the burner, which central opening is surrounded by a number 70 of laterally and radially extending flame openings 3 through which the same mixture is jetted at a reduced pressure upon the tube 75 of the central opening or upon the gas issuing from the central opening, as desired. These flame openings are necessarily small so as to overcome all danger of a flash-back and an explosion.

In the modification shown in Figs. 1 and 2 the burner tube 5 is provided with an 80 elbow 6 connected to a feed pipe 4 and this tube 5 carries at its lower end a nozzle 7 which is preferably provided with a number 85 of external ribs 8 to facilitate cooling through a radiation of heat, and the outer 90 end of this nozzle 7 is provided with suitable screw threads which fit corresponding 95 threads on a smaller nozzle 9, which also has projecting ribs 10 corresponding to the ribs 8, but for an additional purpose. It 100 will be noted that between the ribs 10 and in the cylindrical wall of the nozzle are suitable perforations 3, all of which are radially disposed so that the gas or air which passes through them will flow in the direction of the axis of the nozzle and perpendicular thereto and be preheated by impinging against these ribs 10. The ribs 10 also serve to cause the gas and air to be distributed so that each opening 3 receives the 105 same amount of gaseous fuel. In the center and inner part of the nozzle 9 are suitable screw threads which receive a spindle 11, which has a suitable passage 12 at its lower end which surrounds its axis and running 110 to this passage are suitable transverse openings 13 which run directly to the interior of the tube 5 so that when the mixed air and gas pass into the tube 5 from the elbow 6, the mixed gases flow without substantial 115

reduction of pressure through the passage 12 and through the holes 3. These gases flow with less pressure because of the obstructions incidental to the fins 10. The result of this structure is that when in use, as above described, the combustion is quick and the heat is intense along the axis of the flame, that is about the opening 2 and gas passing through the opening 2 is somewhat preheated by the heating of this tube due to the flames impinged upon it caused by the gases issuing from the holes 3.

In the event that a more powerful flame is desired, this result is obtained by adding to the structure shown in Figs. 1 and 2, several additional shells, as shown in Fig. 5. Here the nozzle 7 rests in and against, with a snug fit, a larger nozzle 14, the inner end of which is reduced at 15 to form a neck which is provided with internal screw threads which engage similar threads on the exterior of the nozzle 7 and exterior screw threads which engage corresponding threads on the outside nozzle 16. The nozzle 16 has suitable unions 17 through which mixed gas and air may be supplied, and it has external fins 18 which are adapted to radiate heat. The nozzle 14 has suitable perforated fins 19 on each side of the openings 3 for the reason above given. When this nozzle is in use, mixed gas and air simultaneously issue from all the openings 3, as well as the opening 2 and the combustion on the interior of the nozzles 9 and 14 is intense, with a corresponding high degree of heat developed in a small space. As above set forth, the quality of the flame, whether for heating or reducing, neutral or oxidizing, according to the desire of the operator, is determined by regulating the valves which regulate the flow of air and gas respectively, to the compressor.

In Fig. 7 a slightly modified structure is shown in that the interior fins 19 of the nozzle 14 are slightly changed in shape, their function being identical with what is above described.

In Figs. 11 and 12 a small burner is shown with a slightly modified structure. Here the spindle 11 is surrounded by a bushing 20 the lower end of which fits snug against this spindle and the upper end of which fits snug in the tubing 5. The upper end of the bushing 20, as well as the upper end of the tubing 5 is closed by a suitable gasket 21 held by a washer 22, which in turn is held by a packing ring 23. Gas reaches the interior of the bushing 20 through a suitable opening 24 which registers with the opening in the elbow 6 and from thence passes through the passage 13 to the passage 12 at the interior of the spindle 11 and also through a passage 25 surrounding the lower end of the bushing 20 and between it and the casing 5 to the perforations 3 at the lower end of the bushing 20 from which the gas and air flow

radially toward the center of the opening 2, as above described. The space 25 about the lower end of the bushing 20 is closed at the exposed end by a suitable internal collar 26, which is preferably made integral with the tube 5.

As the tube about the opening 2 may be exposed to very intense heat, it is preferable to make this of some heat resisting metal such as platinum, although this is not essential, the platinum or other heat resisting metal being used at the outer end only where the greatest heat is found when the burner is in use.

In view of the foregoing, the operation of my improved burner will be readily understood. If it is to be used with a mixture of air and gas, as above described, this mixture is allowed to flow so that a portion passes through the passage 12 in the direction of the axis of the burner and through the opening 2 where it is ignited and more of the mixture at reduced pressure flows through the openings 3 where it is ignited at right angles to the axis of the burner and radially, so that great heat is generated which is caused by combustion taking place in a very limited space and very rapidly, so that great heat is developed in a small space, which heat may be entirely controlled by controlling the proportions of air and gas flowing to the burner and their pressures, and so the flame may be made suitable for heating or reducing or oxidizing or welding, as above described. As the fuel mixture burns without additional air, the flame issuing from the burner may be applied under water or elsewhere out of an atmosphere containing oxygen and at a considerable pressure as compared with the pressures available with unmixed gases, as in an oxy-hydrogen blow-pipe where an excessive pressure will easily extinguish the flame.

By a slight change in structure, that is by closing the passage 13 and extending the passage 12 throughout the length of the stem 11, and then connecting this passage with a source of acetylene gas and oxygen, it is possible to use an acetylene flame for the core of the burner and intensify the heat thereof by the flames issuing from the openings 3, or if desired, a mixture of air and acetylene gas may be passed through this central tube. In any event, the burner may be used in a great number of ways with a great number of variations, according to the results desired.

While I have shown and described several embodiments of my invention, it is obvious that it is not restricted thereto but is broad enough to cover all structures that come within the scope of the annexed claims.

Having thus described my invention, what I claim is,

1. A single burner provided with means

for projecting gaseous and mixed fuel in the direction of its axis and additional means for projecting ignited gaseous and mixed fuel toward the first means above mentioned.

- 5 2. A single burner provided with means for projecting gaseous and mixed fuel in the direction of its axis and additional means for projecting ignited gaseous and mixed fuel radially toward the axis.
- 10 3. A single burner with means for projecting gaseous and mixed fuel in the direction of its axis and additional means for projecting ignited gaseous and mixed fuel toward the first means above mentioned at 15 pressure lower than the pressure of the fuel flowing in the direction of the axis.
4. A single burner provided with means for projecting gaseous and mixed fuel in the direction of its axis and additional means 20 for projecting the same kind of ignited fuel radially at a reduced pressure toward this axis.
5. In a burner, a central part with means for projecting mixed fuel in the direction of

the axis of the burner and a surrounding 25 nozzle with flame perforations therein adapted to cause the flow of gaseous and mixed fuel in the direction of the first means above mentioned of the burner whereby an intensely hot flame may be formed at and im- 30 mediately about the axis.

6. A burner with a central tube surrounded by a plurality of nozzles some of said nozzles having radially disposed perforations through which gaseous fuel may issue 35 and flow in the direction of the axis of the burner.

7. A burner provided with a central portion through which gaseous fuel may flow in the direction of the axis of the burner and 40 a nozzle secured to and surrounding said central portion, said nozzle having radially disposed holes and projecting fins adjacent to said holes whereby preheated gaseous fuel may flow at a reduced and even pressure 45 through said holes and toward the axis of the burner.

ALEXANDER K. SCHAAP.
